ELECTRICAL SYSTEM

Joseph Schaefer, Chicago, Ill.

Original application January 11, 1954, Serial No. 403,312,
now Patent No. 2,831,074. Divided and this applica-
tion April 14, 1958, Serial No. 728,137

6 Claims. (Cl. 338—132)

This invention relates to electrical circuits and more particularly to a novel impedance system wherein current at high voltages may be safely conducted across small contacts arranged to divide the current flow. This application is a division of my copending application, Serial No. 403,312, filed January 11, 1954, now Patent No. 2,831,074, for electrical switch and circuit.

A primary object of the invention is to devise an electrical impedance system for dividing current flow and directing such flow through a plurality of resistances in such manner as to accommodate selection of any desired total resistance.

A more specific object of the invention is to arrange a plurality of impedances, preferably of uniform value, and another plurality of impedances, preferably tapered in value, and to connect one or more of the uniform impedances individually and in series with each other to one or more of the impedances of tapered value in series therewith and in parallel with the rest of the impedances of tapered value.

The foregoing and other objects and advantages of the invention will become apparent from a consideration of the following specification and accompanying drawings, wherein:

Figure 1 is an end elevational view of a preferred embodiment of a switch embodying my invention;

Figure 2 is a sectional view on line 2—2 of Figure 1;

Figure 3 is a sectional view on line 3—3 of Figure 2;

Figure 4 is a perspective view of a drive gear or spool for one of the movable contacts;

Figure 5 is a perspective of a pinion gear for transmitting driving force from a drive gear to its related actuator gear for a movable contact;

Figure 6 is a fragmentary end view similar to Figure 1, but showing a modification of the switch;

Figure 7 is a wiring diagram of a novel rheostat circuit in which the switch is used as a sequential tap switch; and

Figure 8 is a wiring diagram of another novel circuit in which the switch is utilized as a voltage regulator for a transformer.

Describing the invention in detail, the novel switch comprises a plurality of insulator plates illustrated at 2, 4, 6, and 8, although any desired number may be utilized. These plates are mounted on side panels 10 and 12, as for example by three bolt and nut assemblies 14 having spacers 16 to maintain desired spacing between the plates.

Each plate carries pairs of fixed electrical contacts 18 to 39, respectively, in the form of cylinders anchored by screw and nut assemblies 40. Insulator cylinders 42, similarly anchored by screw and nut assemblies 44, are positioned between the pairs of fixed contacts and are preferably of larger diameter than the contacts for a purpose hereinafter discussed.

Each contact 18 to 39 is provided with a connector fin or blade 46 preferably compressed between the contact and its supporting plate by the associated screw and

2

nut assembly 40. The blades 46 are perforated as at 48, to afford convenient connections to associated leads as hereinafter discussed in connection with Figures 7 and 8. It may be noted in this regard that corresponding contacts of the respective plates may be interconnected by such leads, or if desired, all or any desired pairs of contacts may be independently connected to circuits which are to be separately energized and de-energized.

A movable contact 50 is associated with the fixed contacts 18 to 39 of each plate 2, 4, 6, and 8, said contact 50 being preferably in the form of a roller rotatably mounted as at 52 on a plunger 54 received within a spring tube or cage 56 which is manually press-fitted within slots 58 of an electrically non-conductive actuator gear 60 rotatably mounted on a shaft 62. Gear 60 may be conductive if contact 50 is otherwise insulated from shaft 62, or if the contact 50 is itself connected to a lead and is used to close a circuit with each fixed contact. A compression spring 64 is compressed between the gear 60 and the plunger 54 to urge the roller contact 50 into tight engagement with the related fixed contacts.

Each gear 60 is actuated by teeth 66 and 67 of a pinion gear 68 rotatably mounted on a shaft 70. In the illustrated embodiment of the invention, the teeth 67 are mutilated, so that all teeth 66 and 67 mesh with teeth of the related gear 60, but only the teeth 66 mesh with three pairs of teeth 72 of a drive gear or spool 74 having a flange 76 comprising notches 78 aligned with the spaces between the respective pairs of teeth 72.

By means of this novel construction, two of the unmutilated teeth 66 of pinion gear 68 ride on the flange 76 locking the gear 68 against accidental rotation until one of the teeth 72 engages a mutilated tooth 67 whereupon pinion gear 68 is rotated 90° to actuate its roller contact 50 from a closed or "make" position with respect to one pair of fixed contacts 18 to 39 to a closed or "make" position with respect to the next adjacent pair of fixed contacts 18 to 39.

The gears 74 are keyed to a rotatable shaft 80 and are arranged, as best seen in Figure 1, so that the roller contacts 50 are preferably sequentially actuated. In the illustrated embodiment, 30° rotation of the shaft 78 actuates the roller contact 50 associated with one of the plates, for example plate 2. Rotation of the shaft 80 through another 30° increment in the same direction actuates the roller contact 50 of plate 4. Rotation of the shaft 80 through a third increment of 30° in the same direction actuates roller contact 50 of plate 6. Rotation of the shaft 80 through a fourth increment of 30° in the same direction actuates the roller contact 50 of plate 8, etc.

Thus, it will be understood that the shaft 80 is geared to each pinion gear 68 at a 3 to 1 ratio in the illustrated embodiment, so that one complete rotation of shaft 78 actuates each of the roller contacts 50 three times in a sequential relationship with respect to the other roller contacts 50, although it will be understood that any desired ratio may be utilized.

The shaft 80 may be provided with a handle 82 or any other suitable actuating means (not shown) for manual or powered rotation of shaft 80 in both directions.

It may also be noted that as each roller contact 50 is actuated it rolls across one of the insulator cylinders 42 which separate the pairs of fixed contacts. For example, as shown in Figure 2, roller 50 has moved from its closed or "make" position relative to a pair of contacts 28 and 29 toward a closed or "make" position with respect to another pair of contacts 30 and 31. However, the insulator cylinder 42 between contacts 29 and 30 positively prevents any possibility of a short circuit therebetween. This action may be accomplished, as illustrated, by providing insulators 42 of larger diameter than contacts 18

to 39 or by any other construction wherein the insulators 42 are closer than the contacts to the rotational axis of gears 60.

The contacts of each plate 2, 4, 6, and 8 may be regarded as a bank of contacts, with insulators 42 between the pairs of contacts in each bank.

Figure 6. shows a modification wherein one contact of each pair is integral with corresponding contacts of adjacent insulator plates. For example, a continuous contact rod 84 is substituted for the contacts 18 of Figures 1 and 2, and similar rods are substituted for contacts 20, 22, 24, 26, 28, 30, 32, 34, 36, and 38 of the previous embodiment shown in Figures 1 and 2. The ends of these rods 84 are secured to a pair of insulator plates 86 and 88 as by nuts 90, and one end of each rod 84 is provided with an additional nut 92 affording convenient means for attaching a lead 94. Also in Figure 6, the insulator cylinders 42 are replaced by continuous insulator rods 96, one of which is shown in this figure. All other parts of Figure 6. are identical with those of Figures 1 to 5 and are identified by corresponding numerals; although Figure 6 is fragmentary to illustrate the above described modifications of the switch shown in Figures 1 to 5.

The modification of Figure 6 is particularly adapted to the novel rheostat system shown in Figure 7, wherein it will be seen that the contact rods 84 are connected to resistances Z-1 to Z-9 arranged in series. These are preferably the main resistances and should be able to carry the full current in the rheostat.

In the diagram of Figure 7, the insulator plates are shown at 2, 4, 6, and 8, and two additional plates are shown at 2a and 4a. Dividing resistors D-1 to D-6 are connected in parallel with each other, each dividing resistor being connected to the fixed contacts 19, 21, 23, 25, 27, 29, 31, 33, 35, and 37 of one insulator plate. The resistors Z-1 to Z-9 and resistors D-1 to D-6 are shown conventionally and may be simple resistors having fixed resistance values or may be conventional adjustable resistors which may be adjusted to any predetermined value. With alternating current, reactors may be substituted for resistors to provide voltage or current regulation.

The system shown in Figure 7 depicts a 250 ampere load rheostat (25 to 250 volts) that uses a six plate sequential switch such as those shown in Figures 1 to 6. Resistance values are shown in the diagram by way of example, and it will be noted that in order to stay within the current rating of the contacts (nominally 50 amperes) it is preferable to taper the resistance values of the dividing resistors D-1 to D-6, as for example in the manner indicated in Figure 7.

The minimum resistance of the rheostat shown in Figure 7 is 0.1 ohm at step 1 whereat movable contacts 50 connect the fixed contacts 19 to the related contact rod 84. Under these conditions current flow across resistors D-1 to D-6 is respectively, 50 amps., 48 amps., 44 amps., 40 amps., 34 amps., and 29 amps.

At step 2 the movable contact 50 of plate 2 connects the fixed contact 21 thereof to the related contact rod 84, so that the total resistance in the rheostat is about 1.05 ohm which is the value of D-1 and Z-1 in series and in parallel with the value of D-2 to D-6 in parallel. Under these conditions current flow across Z-1 is 44 amps. and current flow across D-1 to D-6 is, respectively, 44 amps., 50 amps., 46 amps., 42 amps., 36 amps., and 31 amps.

At step 3 the movable contact of plate 4 connects its fixed contact 21 to the related contact rod 84, so that the total resistance in the rheostat is about 1.14 ohm which is the value of D-1 and D-2 in parallel and in series with Z-1, in parallel with the value of D-3 to D-6 in parallel. Under these conditions current flow across Z-1 is 81 amps., and current flow across D-1 to D-6 is, respectively, 41 amps., 40 amps., 50 amps., 46 amps., 39 amps., and 34 amps.

At step 4 the movable contact 50 of plate 6 connects its fixed contact 21 to the related contact rod 84, so that

the total resistance in the rheostat is .129 ohm which is the value of D-1 to D-3 in parallel and in series with Z-1, in parallel with the value of D-4 to D-6 in parallel. Under these conditions, current flow across Z-1 is 119 amps., and current flow across D-1 to D-6 is, respectively, 42 amps., 40 amps., 37 amps., 51 amps., 46 amps., and 38 amps.

At step 5, the movable contact 50 of plate 8 connects its fixed contact 21 to the related contact rod 84, so that the total resistance in the rheostat is .148 ohm, which is the value of D-1 to D-4 in parallel and in series with Z-1, in parallel with the value of D-5 and D-6 in parallel. Under these conditions, current flow across Z-1 is 157 amps., and current flow across D-1 to D-6 is, respectively, 43 amps., 42 amps., 38 amps., 34 amps., 51 amps., and 44 amps.

At step 6, the movable contact 50 of plate 2a connects its fixed contact 21 with the related contact rod 84, so that the total resistance in the rheostat is .172 ohm, which is the value of D-1 to D-5 in parallel and in series with Z-1, in parallel with D-6. Under these conditions, current flow across Z-1 is 199 amps., and current flow across D-1 to D-6 is, respectively, 46 amps., 45 amps., 41 amps., 37 amps., 32 amps., and 51 amps.

At step 7, the movable contact of insulator plate 4a connects its fixed contact 21, with the related control rod 84, so that the total resistance in the rheostat is .20 ohm, the value of D-1 to D-6 in parallel and in series with Z-1. Under these conditions, current flow across Z-1 is 250 amps., and current flow across D-1 to D-6 is, respectively, 50 amps., 48 amps., 44 amps., 40 amps., 34 amps., and 29 amps.

The above values are approximate, and successive steps in the rheostat would have the same current division and voltage values if the current is maintained at 250 amps.

The maximum total resistance value in the system of Figure 7 is reached when the sequential operation of contacts 50 finally engages all contacts 50 with the fixed contacts 37 and the related contact rod 84, so that the total resistance value is 1.0 ohm, which is the value of D-1 to D-6 in parallel and in series with the value of Z-1 to Z-9 in series.

By proper adjustment of the resistance values and ratios of Z-1 to Z-9 and D-1 to D-6, the current in the contacts can be held to a maximum permissible value that they can safely make and break. The voltage across resistors D-1 to D-6 is the voltage which is broken by the contacts. Increasing the number of series resistors Z-1 to Z-6 (as for example by using all of the odd numbered contacts of Figures 1 and 2), and decreasing values of D-1 to D-6 results in smaller voltage drop that the contacts must break.

In this manner, a heavy current rheostat may be provided with small contacts by subdividing the heavy current into a larger number of smaller parallel currents.

Figure 8 is similar to Figure 7, and corresponding parts are identified by corresponding numerals; however, in the circuit of Figure 8, the resistors are replaced by transformer taps Z-1 to Z-6 of a conventional insulating or potential transformer 100 to produce a voltage regulator therefor. In this arrangement, four insulator plates and four dividing resistors D-1 to D-4 are used; however, more may be added if desired. Similarly, the novel system may be utilized as a voltage regulator for an auto transformer.

I claim:

1. A voltage and current regulator comprising a plurality of banks of fixed contacts, the contacts of each bank arranged in pairs, a plurality of resistors connected in series to each other, one contact of each pair being connected to corresponding contacts of the other banks and to one side of the related resistor, a plurality of dividing resistors connected in parallel to each other, the other contact of each pair being connected to corresponding contacts of the same bank and to one side of

the related dividing resistor, and a plurality of movable electrically conductive means insulated from each other and each associated with one only of said banks for connecting contacts of its respective pairs.

2. A voltage and current regulator system, comprising at least two banks of contacts, the contacts of each bank arranged in pairs, a plurality of impedances connected in series to each other, one contact of each pair connected to a corresponding contact of an adjacent bank and to one side only of one of said impedances, a plurality of dividing impedances connected in parallel to each other, the other contact of each pair connected to corresponding contacts of the same bank and to one side of one of said dividing impedances and a plurality of movable electrically conductive means insulated from each other and associated each with one only of said banks for selectively interconnecting contacts of its respective pairs.

3. In a voltage and current regulator system; the combination of a plurality of uniform impedances in series, a plurality of tapered impedances in parallel, and means for connecting each of said uniform impedances, individually or in series with one or more of other of said uniform impedances, to one or more of said tapered impedances in series therewith and in parallel with the other of said tapered impedances.

4. In a voltage and current regulator system; the combination of a plurality of impedances in series, another plurality of impedances in parallel, and means for connecting one or more of said first-mentioned impedances, individually and in series with each other, to one or more

of said second-mentioned impedances in series therewith and in parallel with the rest of said second-mentioned impedances.

5. In a voltage and current regulator system; the combination of a plurality of uniform impedances in series, contact bars each connected between adjacent impedances, a plurality of tapered impedances in parallel, a plurality of contacts connected to each of said tapered impedances, and a plurality of relatively movable electrically conductive means insulated from each other and each associated with one only of said tapered impedances for connecting the contacts of respective tapered impedances in step by step manner with the respective bars.

15 6. In a voltage and current regulator system; the combination of a plurality of impedances in series, spaced contact elements, each connected to and between a pair of said impedances, a plurality of impedances in parallel, a group of first contacts connected to respective parallel impedances, a group of second contacts connected to the first contacts, and relatively movable electrically conductive means insulated from each other and each associated with one only of said parallel impedances for successively connecting the first contacts in a sequence 20 to one element and for then successively connecting the second contacts in the same sequence to another element.
